UNITED STATES PATENT OFFICE.

DANIEL TUHEY, OF DAYTON, OHIO.

INTERNAL-COMBUSTION ENGINE.

1,218,132.

Specification of Letters Patent. Patented Mar. 6, 1917.

Application filed September 25, 1916. Serial No. 121,912.

To all whom it may concern:

Be it known that I, DANIEL TUHEY, a citizen of the United States, residing at Dayton, in the county of Montgomery and 5 State of Ohio, have invented a new and useful Improvement in Internal-Combustion Engines, of which the following is a specification.

This invention relates to a new and useful improvement in internal combustion engines.

The principal object of the invention is to provide simple and efficient means for lubricating the piston of an internal combustion 15 engine in such a manner that little or no carbon will be deposited in the cylinder. The lubricant that I preferably employ is water, which, when used, will leave no deposit of carbon; and if a small quantity of 20 oil is employed in my improved lubricating means, the carbon deposited will be almost negligible.

The preferred form of embodiment of my invention is illustrated in the accompanying 25 drawing, of which the figure is a sectional view of an internal combustion engine-cylinder provided with my improved lubricating means for a piston shown therein.

Throughout the specification and drawing, similar reference characters denote corresponding parts.

In a detailed description of the preferred form of embodiment of my invention, the numeral 1 designates an explosive engine 35 cylinder, provided with a water jacket 2 and spark plug 3. Movable within the cylinder 1 is a piston 4 to which a connecting rod 5 is attached by means of a wrist pin 6.

Provided in the lower end of the cylinder 40 1 is a stuffing box 7 which is preferably formed by so enlarging the lower portion of the bore 8 that a space, rectangular in cross section, is provided to receive the following parts. Surrounding the piston 4 in the 45 stuffing box 7 is a metallic member 9 containing an annular chamber 10. This chamber is open around the said piston for the purpose of delivering a lubricating fluid thereto. This fluid is preferably water, 50 since the latter contains no carbon, and is admitted to the chamber 10 by the following

means, although any other suitable construction for this purpose may be employed without departing from the spirit of my invention.

55

Communicating with the annular chamber 10 is a tubular passage 11 which extends through the side wall of the member 9. As the latter is movable within the stuffing box 7, the passage 11 is adapted to be brought 60 into registry with a similar tubular passage 12 which extends through the cylinder wall 12 which extends through the cylinder wall for connection to any suitable fluid-delivering means.

Asbestos packing 13 is preferably placed 65 above the movable member 9 within the stuffing box 7, while similar packing 14 is compressed below it by the follower 15. This follower is pressed against the packing 15 by bolts 16 which enter the cylinder wall 70 from below, after being passed through an annular rim or flange 17 that extends laterally from the bottom portion of the follower. The packing 13 and 14 is designed 75 not only to prevent leakage of the lubricating fluid past it, but also to support the movable member 9 which contains the lubricating chamber 10. However, any other suitable means for supporting the latter may be employed if desired.

80

It is now obvious that the lubricating fluid is supplied entirely by the annular chamber 10 of the member 9 through which the piston 4 passes at the lower end of the cylinder. Water can be effectively employed as the lubricating fluid in my improved construction, although oil may be used if desired. However, water is preferred, since no carbon will be deposited thereby in the cylinder. On the other hand, 90 if oil is used, very little carbon will be deposited, since the packing in my improved lubricating device is arranged to thoroughly wipe the reciprocating piston.

85

I do not wish to be limited to the details 95 of construction and arrangement herein shown and described, and any changes or modifications may be made therein within the scope of the subjoined claim.

Having described my invention, I claim: 100
In an internal combustion engine, a piston movable therein, a stuffing box provided

in the lower end of said cylinder by an enlargement of the bore thereof, a circumferential member in the stuffing box through which the piston passes, packing above and below said member within the stuffing box, a follower adjustably secured to the latter for compressing the packing about the circumferential member, and an annular cham-

ber provided within said member to supply a lubricating fluid to the piston.

In testimony whereof I have hereunto set my hand this 21st day of September, 1916.

DANIEL TUHEY.
